(57) **CLAIM**

We claim the ornamental design for a support assembly for a gas cylinder, as shown and described.

DESCRIPTION

FIG. 1 is a rear elevation view of a support assembly for a gas cylinder, showing our new design;

FIG. 2 is a front elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a top, front and left side perspective view thereof;

FIG. 8 is a top, front and right side perspective view thereof;

FIG. 9 is a top, rear and right side perspective view thereof;

and,

FIG. 10 is a top, rear and left side perspective view thereof.

The broken lines shown in the figures are included for the purpose of illustrating portions of the support assembly for a gas cylinder and form no part of the claimed design.
